UNITED STATES PATENT OFFICE.

WILLIAM WATSON CAMP, OF STRATFORD, ONTARIO, CANADA.

METHOD OF TREATING PEAT-BOGS TO EXTRACT THE WATER FROM THE PEAT IN THE BOGS.

1,399,847.

Specification of Letters Patent. Patented Dec. 13, 1921.

No Drawing.

Application filed March 8, 1920. Serial No. 364,273.

To all whom it may concern:

Be it known that I, WILLIAM WATSON CAMP, of the city of Stratford, in the county of Perth, in the Province of Ontario, 5 Canada, have invented certain new and useful Improvements in Methods of Treating Peat-Bogs to Extract the Water from the Peat in the Bogs, of which the following is the specification.

10 My invention relates to an improved method of treating peat bogs to extract the water from the peat in the bog and primarily compress the peat, and the object of of the invention is to separate the water 15 from the peat and thereby enable the water to evaporate or to be drained off and the peat removed with a minimum amount of moisture, so that it may be compressed where desired by a suitable machine into 20 blocks for fuel or other purposes.

A further object is to effect this treatment of the bog with a minimum amount of power and at a minimum expense and thereby enable peat bogs to be utilized in a commercial 25 way, which has heretofore not been found practical on account of the exorbitant cost of treatment, which has rendered peat as a fuel an impossible competitor with other fuels, such as coal.

30 To effect these objects I follow the following method:

I first excavate the bog by any suitable excavating machine and for any predetermined width and depth according to the 35 capacity of the machine throwing the excavated peat upwardly into a suitable macerator from which it is precipitated back again into the bog behind the machine.

It is then preferably packed by a suitable 40 packing machine, so that it practically occupies the same or less space than what it formerly occupied in its natural state in the bog.

45 After the packing has been accomplished and the surface rendered firm again I preferably treat it with a suitable perforating machine consisting of a series of rods held in plates. These rods are preferably placed about two inches apart and the plates to 50 which they are secured are given an oscillating movement under pressure, whereby the rods practically trowel the interior contour of the hole and thereby permit of the ready withdrawal of the rods.

55 This action of the rods and the machine

whereby the plates carrying the rods are made to travel and are given the desired movement and pressure form no feature in the present invention but will be made the subject matter of a separate application. 60

It is essential, however, that this perforation of the surface of the bog be performed and I find in practice that the desired depth to make the holes is approximately twelve to fifteen inches. 65

While I preferably perforate the newly formed surface of the bog immediately after being excavated and packed as hereinbefore described it will, of course, be understood that this operation may be performed at any 70 convenient time such as in the spring of the year, it being, of course, necessary that it be done when the bog is wet.

The result of this perforation is to compress the peat and squeeze the water therefrom, so that the water will occupy the holes made by the rods aforesaid. As a consequence the evaporation of the water is facilitated to the greatest extent and I find in practice that evaporation will actually take 80 place so rapidly that the holes are practically free from water on a good dry day within three or four hours practically as quickly as evaporation would take place if the holes were made in clay. 85

After the water has been evaporated as aforesaid I then preferably plow the surface of the bog so treated leaving the furrows longitudinally in their natural state after being plowed so that the air and sun 90 will further remove the moisture. The perforations in the furrows allow of the circulation of the air, and, therefore, materially assist drying the separated peat. These separated furrows can now be loaded into 95 wagons and either used as fuel or may be transferred to any suitable compressing plant, where they may be manufactured into blocks, thereby greatly reducing the bulk and making the peat suitable for transshipment. 100

When the peat is first plowed up it will dry down to about thirty per cent. moisture and it will, therefore, be understood that it may be utilized for a fuel in this condition 105 or for other purposes, such as a fertilizer.

I should mention that the peat in its original condition before being excavated and packed as hereinbefore described is lighter than water. In fact in a peat bog 110

under ordinary conditions it is floating in the water in the bog, but after being excavated, macerated and packed it then becomes heavier than water and practically 5 impervious to water and thereby sinks to the bottom of the bog where if the surface of the ground is uneven it will follow the contour of the surface and thereby force all the excess water at the bottom of the bog 10 out and take its place.

Such a method as I describe is revolutionary in the peat industry as all artificial drying is dispensed with and the great expense incident thereto. A bog of one hundred 15 acres and eight feet in depth, which would ordinarily take thirty years to obtain all the peat therefrom can now be utilized in less than six years and at a greatly reduced overhead cost, that is to say at approximately 20 thirty cents a ton by my method as compared with three dollars a ton by the best of the methods at present in use.

This greatly reduced cost is partly accounted for by reason of the fact that the bog may be prepared in any weather rain 25 or shine, which it is not possible to do according to methods now employed.

What I claim as my invention is—

30 1. The method of treating peat bogs to extract the water from the peat therein consisting in excavating the bog uninterrupted step by step the desired depth to form a cavity, then macerating the excavated 35 peat and then feeding such peat again into such cavity, which is continually formed by the ejection of the previously excavated peat.

2. The method of treating peat bogs to 40 extract the water from the peat therein consisting in excavating the bog step by step the desired depth, then macerating the ex-

cavated peat and then feeding such peat down into the cavity, which is continually formed by the ejection of the previously 45 excavated peat, then packing the macerated peat in such cavity.

3. The method of treating peat bogs to extract the water from the peat therein consisting in excavating the bog step by step 50 the desired depth, then macerating the excavated peat and then feeding such peat down into the cavity, which is continually formed by the ejection of the previously 55 excavated peat, then packing the macerated peat in such cavity, then perforating the newly formed surface of the bog.

4. The method of treating peat bogs to extract the water from the peat therein consisting in excavating the bog step by step 60 the desired depth, then macerating the excavated peat and then feeding such peat down into the cavity, which is continually formed by the ejection of the previously 65 excavated peat, then packing the macerated peat in such cavity, then perforating the newly formed surface of the bog and separating the perforated strata from the mass beneath.

5. The method of treating peat bogs to 70 extract the water from the peat therein consisting in excavating the bog step by step the desired depth, then macerating the excavated peat and then feeding such peat down into the cavity, which is continually 75 formed by the ejection of the previously excavated peat, then packing the macerated peat in such cavity, then perforating the newly formed surface of the bog, and then separating the perforated strata from the 80 mass beneath and exposing the separated perforated portions of peat to the air.

WILLIAM WATSON CAMP.
